UNITED STATES PATENT OFFICE.

JOHN A. STEVENS, OF LOWELL, MASSACHUSETTS, ASSIGNOR TO THE UPSON COMPANY, OF LOCKPORT, NEW YORK, A CORPORATION OF NEW YORK.

MANUFACTURE OF SHEETS, BOARDS, AND OTHER MATERIALS.

Application filed May 10, 1928. Serial No. 276,797.

My present invention relates to the manufacture of sheets, boards and other material forms as a continuous process, and more particularly to the forming of a composite sheet by a method and with a machine contrived to draw a continuous strip through a forming apparatus, and it has for its object to provide a method and a machine for this purpose, wherein the friction in the forming apparatus with the drawing means located at the far end of the machine will be greatly reduced. The invention in general is addressed to the proposition of creating and maintaining between one or both faces of the continuously forming and moving strip, and its continuous shaping or treating surfaces, a cushion of gaseous material that greatly facilitates the work of so drawing the strip through the shaping means.

To these and other ends the invention resides in certain improvements and combinations of parts, all as will be hereinafter more fully described, the novel features being pointed out in the claims at the end of the specification.

In the drawings:

Fig. 1 is a largely diagrammatic view partly in section of a sheet forming material of a nature to which my present improvements are adapted;

Fig. 2 is a top plan view thereof;

Fig. 3 is an end view (with reference to the direction of travel of the sheet) of a pair of platens constructed in accordance with, and illustrating one embodiment of, my invention;

Fig. 4 is an end view of one of the platens, showing in dotted lines the manner in which the face plate and the back plate thereof are connected;

Fig. 5 is a plan view of an end fragment of one of the platens;

Fig. 6 is a section therethrough taken on the line 6—6 of Fig. 5, but with the connections for the attachment of the source of supply of gaseous or liquid material omitted. (Any or all hollow staybolts may be used for this purpose.)

Fig. 7 is an enlarged fragmentary detailed section also taken in the plane of the line 6—6 of Fig. 5, showing the aforesaid connection, as an example of one method of connecting the piping or tubing for the admission of gaseous or liquid material for the

incidental film lubrication, so to speak, and also for the admission of materials for surface finishing of the product, such as different grades of paint, varnish or any liquid material which might be wanted on the material as it leaves the platen system. 60

Similar reference numerals throughout the several views indicate the same parts.

Although applicable in other instances, the present invention has been designed in 65 the embodiment shown to facilitate the manufacture of a particular type of board sheets or other material for building or other construction, said board or other material embodying generally two facings or liners of 70 paper enclosing an interior body of mineral or other material, the latter added for the purpose of strengthening and stiffening the board and also rendering it a water-resisting, fire-resisting, and sound and shock-75 proof agent. An example of such board is one in which a mixture containing silicate of soda and dolomitic limestone or other material is introduced between liner sheets and then heat treated at a temperature sufficient 80 to intumesce the said mixture, and cause it, when hardened, to form a firm cellular mass between the liners. The heat is applied and the ultimate thickness of the board determined by drawing it through a plurality of 85 steam, or otherwise heated platens arranged in opposed and suitably spaced sets. When the board or sheet emerges from these platens through the functioning of the drawing means, it is hardened and cut into appropriate lengths. As before indicated the object 90 of the present invention is to reduce the friction incident to drawing the strip through great lengths of such platens, such length being, in the contemplated machine, 95 as much as 160 feet.

Referring first to the showing of Figs. 1 and 2, 1 indicates a supply roll furnishing the upper paper liner which passes therefrom under a guide roll 2, and over a roll 3, 100 by which it is reversed in direction and passes to the heating element, which is also a forming element consisting of an upper series of steam heated platens 4, and a lower series of steam heated platens 5. A supply roll 6 of paper furnishes the lower liner and the strip or web therefrom passes over a roller 7, thence under roller 3, and on between the aforesaid heating and forming platens 4 and 5. The rollers 3 and 7 are 105 110.

companion rollers, driven in opposite directions toward each other at the bottom or mouth of a suitable hopper 8, containing the mixture, in a plastic state of the mineral substances aforesaid making up the filling or interior body of the board. This material feeds in, under suitable regulations, between the liners and passes with them through the platens 4 and 5 by which it is intumesced.

Beyond the platens at the far end of the machine is a hardening oven, indicated generally at 9, through which the composite board indicated generally at 10 in Figs. 1 and 2 is drawn by suitably driven and tensioned drawing or feeding rolls 11. The purpose of the hardening oven 9 in the instance shown is to render the board sufficiently firm to meet the pulling roll without harm to the interior cellular structure thereof, which has been created by the passage through the heated platens. Nevertheless, there is a considerable strain upon the board at the pulling or feeding point, due to the distance between the latter and the front end 25 of the machine from which the materials are initially fed.

In the practice of my present invention, I reduce this resistance, and facilitate the passage of the composite web between the platens, by introducing a volume of air, steam or other heated gaseous material or liquid between one or both surfaces of the liners, and the contiguous faces of the platen, so that a cushion is formed in each instance, over which a product rides in a substantially frictionless and easy manner. To this end I prefer to construct the platens as shown in detail in Figs. 3 to 7. Each platen unit embodies a back plate 12, and a face plate 13 on the inner side, connected by side walls 14, preferably let into grooves or channels in the two plates, and welded thereto at 15. The plates are further intermediately held together by staybolts 16 and 17, the ends of which are riveted into counter-sinks 18 in the plates. A hollow platen is thus produced into which steam or another suitable heating agent may be introduced by supply connections 19, and exhaust connections 20.

The lower platens 5 through extensions 21 at their ends perforated at 22 are carried on vertical guide rods 23 and supported by rigid sleeves 24 threaded on the guide rods and resting upon the frame 25 of the machine. Above these extensions further sleeves 26 threaded on the guide rods support helical compression springs 27 encircling the rods, which springs in turn support similar extensions 28, perforated at 29 on the upper platens 4, whereby the upper platens are resiliently supported to a predetermined amount. The central staybolts or connecting elements 17 are preferably tubular as shown in Figs. 6 and 7, so that

they are capable of conducting a gaseous or other material from the back plate 12 through to discharge upon the surface of the face plate 13 between the latter and the board material 10. For this purpose a 70 threaded socket fitting 30 is suitably secured to the back plate 12 in each instance, the passage in said fitting being registered to communicate with the central passage in the tubular staybolt 17. A nipple 31 provided 75 with a supply pipe 32 coming from a source of steam, air or other suitable gaseous or other material is screwed into the fitting, and thereby a gaseous cushion at a proper temperature not interfering with the heating function and at a suitable pressure is transmitted through each platen, and created upon the face thereof contiguous to the proximate face of the board or other product 10, so that the latter, though controlled as to its thickness by the degree of separation of the opposing platen, nevertheless floats, as it were upon the two pads of air or steam or other material or liquid, which, though almost imperceptible thickness 90 greatly reduces the friction of the product board in its passage between the platens under the impulse of the drawing rolls 11.

The lower platens 5 are preferably relatively thick as shown, and in order to prevent any weaving of the strip during its passage between the two sets of platens, I prefer to provide at each side of the lower set of platens, a side rail or guide rail 33, which may consist of a strip of wood or 100 metal suitably secured to the platen surfaces, as clearly shown in Fig. 3. These strips are of a thickness less than the distance of minimum separation of the two sets of platens, it being necessary, nearly, if they 105 constitute guiding abutments engaging to a greater or less degree the raw edges of the board or strip, which are later trimmed accurately through the functioning not herein shown, because not necessary to be shown. 110

I claim as my invention:

1. In the manufacture of boards and sheets, the method of drawing a continuously forming strip between shaping heat transmitting platens which embodies producing a 115 gaseous or liquid cushion between the surfaces of the strip and the contiguous heat transmitting platens.

2. In the manufacture of boards and sheets, the method of drawing a continuously forming strip between heated shaping faces of the platens which embodies introducing under pressure, a gaseous body between the surfaces of the strip and the contiguous face plates to produce a frictionless cushion in aid 120 of the drawing means.

3. In the manufacture of boards and sheets, the combination with a pair of platens constituting a shaping means for a continuously forming strip and means for drawing 130

the strip through such shaping means, of means for introducing a supply of gaseous material between the strip and the face of a contiguous platen to form a frictionless 5 cushion for the travel of the strip.

4. In the manufacture of boards and sheets, the combination with a pair of platens constituting a shaping means for a continuously forming strip and means for drawing 10 the strip through such shaping means, of means for introducing a supply of gaseous or other material under pressure through one of the platens to the inner face thereof to form a frictionless cushion for the travel of 15 the strip between the latter and the contiguous platen face.

5. In the manufacture of boards and sheets, the combination with a pair of platens or hot plates constituting a shaping means for continuously forming strip and means 20 for drawing the strip through such shaping means, one of said platens comprising a hollow element provided with a tubular connecting member extending from side to side thereof and having a discharge opening on 25 the inner contacting face of the platen, of a supply of gaseous or other material connected to the tubular element to maintain a frictionless cushion of such material between the inner face of the platen and the strip.

JOHN A. STEVENS.
